United States Patent

Des. 238,915

Patented Feb. 24, 1976

238,915

SEAT

Stapleton Long, Morristown, Tenn., assignor to
The Berkline Corporation, Morristown, Tenn.

Filed Sept. 20, 1974, Ser. No. 507,671

Term of patent 3½ years

Int. Cl. D6—01

U.S. Cl. D6—71

FIG. 1.

FIG. 2.

FIG. 3.

FIG. 4.

FIG. 1 is a front perspective view of a seat in the form of an armchair showing my design;

FIG. 2 is a side perspective view thereof;

FIG. 3 is a front perspective view of a seat showing my design in the form of a sofa; and

FIG. 4 is a side perspective view thereof.

The back of the seat is conventional.

I claim:

The ornamental design for a seat, as shown and described.
